CIRCUMCISION CLAMP

Harry O. Maryan, Chicago, Ill.

Application January 3, 1952, Serial No. 264,701

2 Claims. (Cl. 128—346)

1

This invention relates to improvements in circumcision clamps and it consists of the matters hereinafter described and more particularly pointed out in the appended claims.

One of the objects of the present invention is to provide an improved instrument in the form of a clamp which is of a simple construction, may be completely sterilized without damage thereto, may be readily applied in position for a circumcision operation and this in a manner providing ample room for use of the surgeon's knife in removing the prepuce.

Another object of the invention is to provide a clamp of this kind, wherein the clamping action upon the prepuce adjacent the cervix of the glans is imposed with a uniform pressure, thus affording a rapid glutination between the prepuce and its membranous lining, thereby reducing bleeding to a minimum and the suturing often necessary after surgery.

Also it is an object of the invention to provide a clamp of this kind which has a wide range of use, from infants to adults.

Again it is an object of the invention to provide a clamp of this kind, which does not require the holding by hand of any part thereof when applied for a circumcision operation, thus leaving both hands of the surgeon free while performing such operation.

The above mentioned objects of the invention, as well as others along with the advantages thereof will more fully appear as the specification proceeds.

In the drawing:

Fig. 1 is a perspective view of the parts forming the improved clamp arranged in the order of their assembly.

Fig. 2 is a transverse vertical sectional view through a part of the improved clamp, as taken on the line 2—2 of Fig. 1 with the parts in operative position upon the male organ, ready for surgery in removing the prepuce.

Fig. 3 is a bottom view of the base plate of the clamp.

Fig. 4 is a view of one of a number of glans receiving cups and stem therefor forming a part of the clamp.

In general the improved clamp includes a base plate having a plurality of openings therein each flaring downwardly and outwardly toward the bottom and which openings are of different diameters to accommodate penises of different sizes. Associated with the base plate is a plurality of stemmed cups, each sized in diameter for use in an associated opening, the stemmed

5 cups being the same in length. Also associated with the base is an inverted U-shaped yoke that may be positioned for use with a base plate opening of the selected size and up through which the stem of each cup extends so that it may be actuated to impart a straight upward pull thereon, and whereby the cup, in connection with the flared opening in which it is engaged, coacts to uniformly clamp the prepuce and its membranous lining to afford a quick glutinate adhesion around the zone of clamping pressure and which reduces to a minimum, if not completely eliminating bleeding after the surgical removal of the prepuce.

10 15 Referring now in detail to that embodiment of the invention illustrated in the drawings, the improved clamp includes among its parts a rigid base plate 10 which as shown herein may be of an elongated shape with rounded ends.

20 On the median line thereof are longitudinally spaced circular openings 11—12 and 13 respectively of different diameters and each of which have downwardly and outwardly flaring peripheral walls 11^a, 12^a and 13^a respectively. 25 Laterally spaced at each side of each opening 11, 12 and 13 respectively are pilot holes 14. These pilot holes are arranged in the longitudinal margins of the base member, the pilot holes of each pair being spaced apart the same distance from the axis of the associated openings 11, 12 and 13 respectively.

30 The improved clamp also includes an inverted U-shaped yoke 15 that includes a pair of laterally spaced upright legs 16—16 that are connected together at their top ends by a cross bar 17. Centrally in said bar is an unthreaded hole 18. The legs are spaced apart the same distance as a transverse pair of pilot holes 14, the bottom end of each leg being formed with an elongated foot 19 from which depends a stud 20 that is adapted to enter a pilot hole 14. The yoke may be employed with any opening 11, 12 or 13 and its associated pair of pilot holes 14. When so employed its studs 20 are engaged in said holes as in Fig. 2, portions of each foot then engaging upon parts of the top surface of the base member longitudinally at each side of the associated pilot hole.

35 40 45 In this way the yoke is detachably connected to the base plate in an upright position, with the hole 18 in its cross bar 17 arranged in axial alignment with the selected hole 11—12 or 13 with which it is to be used.

45 50 Associated with the base plate and yoke above described is a plurality of members 21, one of

which is shown in Fig. 4 in full lines, another by means of dotted lines and the third by means of dot and dash lines, and each of which includes a bell like cup 22 that is open at the bottom and is provided with a cylindrical stem 23 at the top. All of the cups are of the same length from top to bottom and employ the same diameter in the stem thereof, the upper end of which is threaded at 24. The diameter of the stem is such that it may pass through the opening 18 in the cross bar 17 of the yoke with a fairly snug fit as a sliding bearing. Each cup 22 has a flared bottom portion 25 which is complementary to the flared wall of the opening 11, 12 or 13 with which the member is used. In the upper portion of each cup 22 is a vent opening 26. Thus the various members 21 differ primarily in the size of the cup member 22, each cup being designed to cooperate with only one of the openings 11, 12, or 13.

When the selected member 21 is in operative relation to the base member 10 and yoke 15, the threaded upper portion of the stem 23 extends above the cross bar and a knob like nut 27 is applied thereto with a washer 28 disposed between the base of this nut and the cross bar. The diameter of the flared end 25 of each cup is so correlated with respect to the diameter of the upper end of its associated opening 11, 12 or 13 that it cannot pass upwardly through the same.

In the use of the clamp device above described, the member 21 having the proper size of cup is of course first selected, according to the size of the penis P to be operated upon. After cleansing the penis, if the preputial orifice is too small two mosquito clamps are applied to the preputial ring and the same is put on stretch. A suitably anointed probe is then passed between the prepuce and the glans G to break existing adhesion and free the prepuce from further retraction. The prepuce Pr is then stretched forwardly and the orifice niched between the two clamps to provide a dorsal slit therein. The prepuce is then retracted or pushed back and the exposed glans again cleansed as with a saline sponge to remove smegma.

With the prepuce pushed back or retracted to the neck of the glans and back of the corona thereof, and after anointing the inside of the cup of the selected member 21, it is placed over the glans, allowing parts of the mucous membrane of the prepuce to fit below the corona of the glans. In this fitting of the cone upon the glans, the air in advance of the latter escapes out through the vent 26 of the cup to insure a good complete fit between the glans and cup. The prepuce is now pulled forwardly and over upon the outer surface of the cup and at which time the flare of the cup is engaged at the junction of the prepuce and the gland adjacent the corona of the latter.

With the member 21 so applied, the stem 23 of the member 21 is then inserted through the associated selected opening 11, 12 or 13 in the base plate from its flared bottom end. At this time the yoke 15 is applied to the base member 10 by inserting the studs 20 thereof into the pilot holes 14 associated with the selected opening and also at this time, the stem 23 is passed through the hole 18 in the cross bar 17 of the yoke. Thereafter the washer 28 is dropped over the upper end of the stem (above the cross bar) and the nut 27 then applied to said end of the stem.

By turning the nut in the proper direction, an upward straight line axial lift is imparted to the stem while at the same time the yoke is forced downwardly upon the base member. In this up-

ward movement of the stem, the flared bottom end of the cup approaches more closely to the flared beveled wall of the opening so that the part of the prepuce disposed therebetween is subjected to a uniform clamping action entirely about its circumference. This places said clamped portion of the prepuce under heavy pressure which cuts off the supply of blood to the prepuce outwardly of the clamped part. The parts are permitted to remain in this relationship for about five minutes, which is sufficient to glutinate the prepuce and its mucous membrane and produce a blood free adhesion therebetween in the form of a band.

The excess of prepuce beyond said band is then ready for removal by the surgeon who, using a sharp knifelike instrument, makes an annular slit circumferentially about the base of the excess prepuce, following about the upper end of the selected opening and cutting clear through the prepuce against the outer surface of the cup about a line forming the junction of the flared end with the body of the cup.

Upon removal of the nut the clamp may be taken apart and the cup thereon withdrawn downwardly and outwardly through the opening it before occupied in the base member. Thereafter the cup is removed from the glans and proper dressings applied to the penis.

With the clamp made as described, it is to be noted that the clamping pull on the member 21 is imposed thereon in a straight line axially of the stem of this member. This straight line action is important as it insures a uniform clamping action in a band like area entirely about the base of the prepuce, insuring a complete substantially uniform blood stoppage so that the prepuce and its mucous membrane will glutinate uniformly with an adhesion insuring but the minimum, if any, of bleeding after the operation. Thus there is less danger of infection and healing quickly takes place without the usual soreness.

It is to be further noted that the parts may be readily cleansed and sterilized and that when said parts are in the applied assembled condition both hands of the surgeon performing the operation are free for that purpose.

It will also be observed that only one base, yoke, nut and washer are required for use in performing operations upon penises of different sizes, it being necessary only to have the members 21 of different sizes.

I claim:

1. A circumcision clamp embodying therein, a base member having a downwardly flared opening therein, a glans receiving cup having a flared margin at its bottom end for coacting with the wall of said opening in clamping therebetween the base of the prepuce adjacent its junction with said glans, a stem extending from the top of said cup, a yoke-like member adapted for detachable engagement with said base member when arranged perpendicularly thereto and including laterally spaced legs and a part connecting said legs at the top, coacting means providing a stud and recess interengagement between the bottom ends of said legs and said base member respectively, permitting a separation and an engagement therebetween in the direction of the axis of the stem, and a member engaged with but separable from said leg connecting part of said yoke-like member and from the top end of said stem and operative when turned in one direction to impart an upward axial lift to the stem.

to move the margin of said cup into prepuce clamping cooperation with said wall of said opening and to move said yoke member toward and for holding the same in operative position upon said base member.

2. A circumcision clamp embodying therein, a base member having a downwardly flaring opening therein and a pair of recesses in the top surface thereof spaced outwardly from the periphery of said opening, a glans receiving cup having a flared margin at its bottom end for coacting with the wall of said opening in clamping therebetween the base of the prepuce adjacent its junction with said glans, a stem extending from the top of the cup, a yoke-like member adapted for detachable engagement with said base member when arranged perpendicularly thereto and including laterally spaced legs and a part connecting said legs at the top, studs on the bottom end of said legs for engagement in said recesses

10
20

permitting a separation and an engagement therebetween in the direction of the axis of said stem, and a member engaged with and separable from said leg connecting part of the yoke-like member and from the top of the stem and operative when turned in one direction to impart an upward axial lift to the stem to move the margin of the cup into prepuce clamping cooperation with said wall of said opening and to move said yoke member toward and for holding the same in operative position upon said base member.
